CLAIM

The ornamental design for a pill box as shown and described.

DESCRIPTION

FIG. 1 is a perspective view of the first part showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is a perspective view of the second part showing my new design;

FIG. 10 is another perspective view thereof;

FIG. 11 is a front view thereof;

FIG. 12 is a back view thereof;

FIG. 13 is a left view thereof;

FIG. 14 is a right view thereof;

FIG. 15 is a top plan view thereof;

FIG. 16 is bottom plan view thereof;

FIG. 17 is a partial enlarged view of portion 17 in FIG. 2;

FIG. 18 is a partial enlarged view of portion 18 in FIG. 10;

and,

FIG. 19 is a perspective view of a pill box showing my new design, in the assembled configuration state.

The broken lines depict portions of the pill box and form no part of the claimed design.

1 Claim, 19 Drawing Sheets
